Primary Examiner — Paula Greene*(74) Attorney, Agent, or Firm* — Paul R. Martin(57) CLAIM

The ornamental design for a storage container, as shown and described.

DESCRIPTION

FIG. 1 is a perspective view of my new design for a storage container.

FIG. 2 is another perspective view of my new design for a storage container showing the lid in open position.

FIG. 3 is a top plan view of the storage container shown in FIG. 1.

FIG. 4 is a right side elevational view thereof.

FIG. 5 is a left side elevational view thereof.

FIG. 6 is a front elevational view thereof.

FIG. 7 is a rear elevational view thereof; and,

FIG. 8 is a bottom plan view thereof.

The broken lines form no part of the claimed design.
